UNITED STATES PATENT OFFICE.

SOLOMON C. CHASE, OF NORTH BALTIMORE, OHIO.

MACHINE FOR CUTTING BUNGS.

SPECIFICATION forming part of Letters Patent No. 357,175, dated February 8, 1887.

Application filed April 30, 1886. Serial No. 200,668. (No model.)

To all whom it may concern:

Be it known that I, SOLOMON C. CHASE, a citizen of the United States, and a resident of North Baltimore, in the county of Wood and State of Ohio, have invented certain new and useful Improvements in Machines for Cutting Bungs, &c.; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of my improved machine for cutting bungs or similar wooden disks. Fig. 2 is a longitudinal vertical sectional view of the same; and Fig. 3 is a perspective detail view, on an enlarged scale, of the cutting end of the machine.

Similar letters of reference indicate corresponding parts in all the figures.

My invention has relation to machines for cutting bungs or similar wooden disks; and it consists in the improved construction and combination of parts of such a machine, in which the bung is cut out of a board of a suitable thickness by two revolving cutter-bits revolving around a common center and having means for contracting them as the cutting progresses, so that the bung will receive its proper taper, as hereinafter more fully described and claimed.

In the accompanying drawings, the letter A indicates a frame which is suitably supported, and which is formed with two registering longitudinal bearings, B B, in which the tubular shaft C of the cutter is journaled. An inner tubular shaft, D, slides within the outer tubular shaft, and projects at both ends of the same, and this shaft is provided with a socket, E, in its rear end, within which socket a ball, F, is secured. A lever, G, is pivoted at one end to the rear end of the frame, and bears against the ball in the end of the inner shaft, serving to push the said shaft forward when the outer end of the lever is forced forward. If desired, any other suitable means for forcing the tubular shaft forward may be used, although the lever is the most convenient and simple means for performing the work.

A coiled spring, H, is placed within the rear end of the inner tubular shaft, bearing against

the closed rear end and against a cross-bar, I, which is secured at its ends to the inner sides of the outer tubular shaft and projects through longitudinal slots J J in the sides of the inner shaft, the spring serving to draw the inner tubular shaft rearward after it has been forced forward.

The outer tubular shaft is provided with a belt-pulley, K, upon its middle, over which a drive-belt may pass; or it is provided with any other suitable gear through which rotary motion may be communicated to the shaft.

The forward end of the inner tubular shaft is provided with two diametrically-opposite and laterally-projecting ears, L L, to the ends of which the inwardly-projecting lips M of the bits N and O are pivoted, and the rear ends of these bits are formed each with a pair of inwardly-bent lips, P P, which clamp around and engage grooves Q in the sides of two wedge-shaped guides, R R, secured to the sides of the forward end of the outer tubular shaft. These wedge-shaped guides increase in width toward the forward end of the shaft and cause the grooves and outer edges of the guides to diverge, so that when the inner shaft is pushed forward within the outer shaft the rear ends of the bits will be forced apart, causing the forward cutting ends of these cutters to contract and consequently to cut in a smaller circle than when the shaft is not forced forward, so that a conical block or disk may be cut by gradually forcing the inner shaft forward.

The forward end of the inner shaft is closed and formed with a perforation, through which the shank T of a centering-disk, U, may pass, the said disk being swiveled to the end of the shank and having points V upon its outer face. The inner end of this shank which slides in the perforation is provided with a small disk or head, W, which bears against the forward end of a spring, X, within the shaft, which spring bears with its rear end against a suitable disk or stop, Y, within the shaft, the spring serving to force the shank and centering-disk forward. A laterally-projecting bit, Z, having its outer end bent slightly down, fits adjustably with its shank A' in the forward end of the inner shaft, having a set-screw, B', for adjusting it.

The frame of the machine is provided with

suitable guides, C', or stops, against which a board may be placed and moved transversely to the shaft and to the cutters, and when the machine is in operation the board is placed 5 against the guides with one end opposite to the cutters.

When the shaft is revolved and the proper place of the board to be cut into bungs has been placed opposite to the cutters, the inner 10 tubular shaft is forced forward, causing the centering disk to bear against the portion which will become a bung when finished, while the cutters will cut a groove around the bung, contracting toward the outer end as the inner 15 shaft with the cutters are forced into the board by the lever, and at the time when the cutters are cutting through the board the laterally-projecting bit with the curved end will bear 20 against the face of the bung and trim off the face of the bung and round off the edges, finishing the bung, so that it is ready for use the moment the centering disk and its spring-cushioned shank pushes the finished bung out from 25 between the bits after they have cut through the board.

The cutting end of one bit is provided with two cutting-lips upon its side edges, as shown at D' D', upon the bit N, and the other bit, O, has a cutting-lip, E', upon its inner side edge, 30 so that the one bit will cut both sides of the cut, making room for the other cutter which works up the wood which has been thus cut loose and trims off the side of the bung by its inner cutting-lip. The bit having the two cutting-lips will thus cut chiefly with the cutting-lips, and not with its forward edge, while the bit with only one cutting-lip will cut with its forward edge, the end of the bit being ground off obliquely, as shown at F'.

40 The wedge-shaped grooved guides are secured upon a sleeve, G', which slides upon the forward portion of the outer tubular shaft, and this sleeve is provided with a set-screw, H', by means of which the sleeve may be adjusted so as to force the ends of the bits farther apart or closer together for cutting bungs of 45 different diameters.

Having thus described my invention, I claim and desire to secure by Letters Patent of the 50 United States—

1. In a machine for cutting bungs or similar wooden disks, the combination of an outer tubular shaft having means for revolving it, an inner shaft sliding within the outer shaft 55 and turning with it and having laterally-projecting ears upon its forward end, means for sliding the inner shaft forward and back, bits pivoted near their cutting ends upon the ears of the inner shaft, and wedge-shaped guide-blocks upon the outer tubular shaft having 60 the inner ends of the bits bearing against them, as and for the purpose shown and set forth.

2. In a machine for cutting bungs and similar wooden disks, the combination of an outer tubular shaft having means for revolving it, 65

an inner shaft sliding within the outer shaft and turning with it and having laterally-projecting ears at diametrically-opposite sides of the forward end, means for sliding the inner shaft forward and back, bits pivoted near their cutting ends upon the ears and having inwardly-bent lips upon their inner ends, and wedge-shaped guide-blocks having the forward ends of their outer edges diverging and 70 secured upon the forward end of the outer tubular shaft, and having longitudinal grooves in their sides parallel with the outer edges, and having the lips of the bits sliding in them, as and for the purpose shown and set forth. 75 80

3. In a machine for cutting bungs or similar wooden disks, the combination of an outer tubular shaft having means for revolving it, an inner shaft sliding within the outer shaft and having longitudinal slots in its sides, 85 spring bearing with one end against the closed rear end of the inner tubular shaft within the same, and with its forward end against a cross-bar passing through the slots in the inner tubular shaft from the sides of the outer shaft, a 90 lever bearing against the rear end of the inner tubular shaft, two bits pivoted near their cutting ends upon diametrically-opposite ears of the forward end of the inner shaft, and wedge-shaped guide-blocks upon the forward end of 95 the outer tubular shaft, having their forward ends wider than the rear and having the rear ends of the bits bearing against their edges, as and for the purpose shown and set forth.

4. In a machine for cutting bungs or similar wooden disks, the combination of a shaft having two cutters projecting with their ends at equal distances from the axis of the shaft, and having means for forcing their forward ends together during the progress of the cutting, with a laterally-projecting cutter having its outer end slightly curved and having its shank sliding in the end of the shaft and adjustably secured by a set-screw, as and for the 100 purpose shown and set forth. 105

5. In a machine for cutting bungs or similar wooden disks, the combination of an outer tubular shaft having means for revolving it, an inner shaft sliding within the outer shaft and turning with it and having laterally-projecting ears at diametrically-opposite sides of its forward end, means for sliding the inner shaft forward and back, bits pivoted near their cutting ends upon the ears and having inwardly-bent lips upon their inner ends, 115 and a sleeve sliding adjustably upon the outer end of the outer tubular shaft and provided with outwardly-widening wedge-shaped guide-blocks having grooves in the sides parallel with the outer edges for the reception of 120 the inwardly-bent lips of the rear ends of the bits, as and for the purpose shown and set forth. 125

6. In a machine for cutting bungs or similar wooden disks, the combination of a shaft, a 130 cutter-bit projecting forward from the end of the shaft and having two outwardly-project-

ing cutting-lips upon the side edges of its cutting end, and a cutter-bit secured at an equal distance from the axis of the shaft and having an oblique outer end, forming a sharp forward cutting-edge, and having an outwardly-projecting cutting-lip upon the inner edge of its end, as and for the purpose shown and set forth.

7. In a machine for cutting bungs or similar wooden disks, the combination of a frame having longitudinal bearings and having transverse guides, an outer tubular shaft journaled in the bearings and having [a pulley upon its middle, an inner tubular shaft having a ball in its rear end and having longitudinal slots in its sides and two laterally-projecting ears at its outer end, a spring within the inner tubular shaft bearing against the closed rear end and against a cross-bar projecting from the outer tubular shaft through the slots in the inner shaft, a lever pivoted upon the frame and bearing against the ball in the end of the inner shaft, a centering-disk swiveled upon a shank sliding in the outer end of the inner tubular

shaft and having its inner end bearing against a spring, cutter-bits pivoted near their cutting ends upon the lips of the inner shaft and having inwardly-bent lips upon the inner ends, a sleeve secured adjustably upon the forward end of the outer shaft and provided with two diametrically-opposite wedge-shaped guide-blocks widening toward their forward ends and having longitudinal grooves in the sides, parallel with the outer edges, for the lips upon the bits, and a cutter-bit having its shank secured adjustably in the outer end of the inner shaft, and having its bit bent laterally and curved at the outer end, as and for the purpose shown and set forth.

In testimony that I claim the foregoing as my own I have hereunto affixed my signature in presence of two witnesses.

SOLOMON C. CHASE.
